CLAIM

The ornamental design for a logs rack, as shown and described.

DESCRIPTION

FIG. 1 is a top front perspective view of a log rack, showing my new design;

FIG. 2 is a top plan view thereof;

FIG. 3 is a front elevational view, the rear elevation being a mirror image thereof;

FIG. 4 is a right side elevational view, the left side being a mirror image thereof;

FIG. 5 is a bottom plan view thereof;

FIG. 6 is a top plan view of a second embodiment of a logs rack;

FIG. 7 is a front elevational view, the rear elevation being a mirror image thereof;

FIG. 8 is a front elevational view of a third embodiment of a logs rack, the rear elevation being a mirror image thereof;

FIG. 9 is a front elevational view of a fourth embodiment of a logs rack, the rear elevation being a mirror image thereof;

FIG. 10 is a right side elevational view, the left side being a mirror image thereof;

FIG. 11 is a top perspective view of a fifth embodiment of a logs rack;

FIG. 12 is a top plan view thereof; and

FIG. 13 is a front elevational view, the rear elevation being a mirror image thereof.
